UNITED STATES PATENT OFFICE.

HENRY D. JAMES, OF EDGEWOOD PARK, PENNSYLVANIA, ASSIGNOR TO WESTINGHOUSE ELECTRIC & MANUFACTURING COMPANY, A CORPORATION OF PENNSYLVANIA.

PUSH-BUTTON SWITCH.

Application filed November 20, 1920. Serial No. 425,458.

To all whom it may concern:

Be it known that I, HENRY D. JAMES, a citizen of the United States, and a resident of Edgewood Park, in the county of Allegheny and State of Pennsylvania, have invented a new and useful Improvement in Push-Button Switches, of which the following is a specification.

My invention relates to push-button switches and particularly to such control switches as are employed to intermittently open and close an electric circuit or to control relays or like apparatus through an auxiliary circuit.

The object of my invention is to provide a switch of the character described which possesses the advantages of simplicity, efficiency of operation and cheapness.

The preferred form of my invention is shown in the accompanying drawing, wherein—

Figure 1 is a side view, partially in elevation and partially in section, of a switch embodying my invention;

Fig. 2 is a plan view thereof, and

Fig. 3 is a view, partially in elevation and partially in section, looking from the left of Fig. 1.

The switch comprises a base 4 to which are secured contact supports 5, 6 and 7 that are provided with terminals 8, 9 and 10, respectively. A movable contact member or finger 11, which is made of steel or some other flexible conducting material, is also secured to the base and has one end thereof fastened to the support 5.

The finger 11 has a contact tip 12 of conducting material, such as copper, formed on its free end, which is adapted to be moved into and out of engagement with stationary contact members 13 and 14 that are carried by supports 6 and 7, respectively, to open and close circuits through the terminal members 8 and 9 and terminal members 8 and 10, respectively.

A cover 16 has a lining 17 of fish paper or other non-conducting material and an outer portion stamped out of sheet metal. The cover is provided with a depending tubular portion 18 through which a push button 19 extends, and which serves as a guide to maintain the push button in proper alignment.

The push button 19 is provided with a pair of projections 20 having alined holes

therein to receive a pin 21. The contact finger 11 extends through the space between the projections 20 and above the pin 21 and the latter prevents accidental removal of the push button from the contact finger.

The push button 19 has a recess 22 for the reception of a coil spring 23 which is compressed between the top surface of the contact finger 11 and the upper wall of the recess.

The contact finger, being of resilient material, normally occupies the position shown in Fig. 1 to close a circuit through the terminals 8 and 10. When the button is compressed, that circuit is broken and another circuit is closed, through the terminals 8 and 9.

The yielding connection between the push button 19 and the contact finger 11 permits the shoulder portion of the button to be normally maintained in engagement with the inner end of the depending portion 18 of the cover 16, thus excluding dirt and moisture from the interior of the switch, and the lost-motion connection between the push button and the contact finger also permits the button to slide freely in the portion 18. The contact finger moves through an arc, while the lost-motion connection permits the push button to move in a straight line.

While I have shown my construction as applied to a switch of the double-pole type, it could, if desired, be employed in single-pole constructions, as, for instance, to control switches whereby the circuit is normally kept closed or in switches employed for intermittently closing a circuit.

Various modifications may be made in the construction without departing from the spirit of the invention, as set forth in the appended claims.

I claim as my invention:

1. In an electric switch, a stationary contact member, a movable contact member normally yieldingly held in engagement with the stationary contact member, a push button for actuating the movable contact member, a guide for the push button, and a yielding connection between the push button and the movable contact member for permitting the push button to be guided through a path of travel independent of the direction of movement imparted to the movable contact member.

2. In combination, in an electric switch, a

- base, a cover provided with an opening therein, a contact member movable through an arcuate path, a vertically movable push button loosely mounted on the movable contact member, a spring interposed between the push button and the movable contact member, and a guide member for the push button whereby such button is maintained against horizontal movement.
- 5 3. In an electric switch, the combination with a stationary contact member, of a spring contact finger having a contact member movable in an arc of a circle and normally in engagement with said stationary contact member and a push button for actuating the movable contact finger and resiliently connected thereto, whereby said contact finger may simultaneously maintain the engagement of said contact members and retain the push button in its inoperative position.
- 10 4. The combination with an electric switch provided with a stationary contact element and a contact member movable through an arc of a circle that is biased into engagement with said element, of a cover therefor provided with a combined guide and seating member, a push button extending through the guide member and provided with a seat-engaging portion, and means

constituting a yielding lost-motion connection between said push button and said contact member for normally yieldingly maintaining the push button against its seat.

5. The combination with an electric switch provided with a stationary contact element and a contact member movable through an arc of a circle into and out of engagement with said element, of a cover therefor provided with a combined guide and seating member, a push button extending through the guide member and provided with a seat-engaging portion, means for normally yieldingly maintaining the push button against its seat, and constituting a lost motion connection between the push button and the said contact member, the said connection permitting relative movements of the push button and the contact member, in directions longitudinally of the button and of the contact member, respectively, and permitting, also, the simultaneous engagement of the contact element by the contact member and the actuation of the push button to its seat-engaging position.

In testimony whereof, I have hereunto subscribed my name this 4th day of November, 1920.

HENRY D. JAMES.
